OTHER PUBLICATIONS

Official Action Dated Apr. 5, 2018 From the U.S. Patent and Trademark Office Re. U.S. Appl. No. 29/609,712. (6 pages).

Primary Examiner — Janice Hallmark

Assistant Examiner — Harold E Blackwell, II

(57) **CLAIM**

The ornamental design for spacer, as shown and described.

DESCRIPTION

FIG. 1 is a perspective front view of a spacer, showing my new design;

FIG. 2 is a perspective rear view thereof;

FIG. 3 is a front right view thereof;

FIG. 4 is a front left side view thereof;

FIG. 5 is a rear side view thereof;

FIG. 6 is a top view thereof; and,

FIG. 7 is a bottom view thereof.

The broken lines in the drawings illustrate portions of the spacer that form no part of the claimed design.

1 Claim, 7 Drawing Sheets
